Primary Examiner — Kevin Rudzinski(74) *Attorney, Agent, or Firm* — Renner, Otto, Boisselle & Sklar, LLP(57) **CLAIM**

The ornamental design for a luminaire, as shown and described.

DESCRIPTION

FIG. 1 is a perspective view of the luminaire according to my new design;

FIG. 2 is a top view of the luminaire shown in FIG. 1;

FIG. 3 is a front view of the luminaire shown in FIG. 1; and,

FIG. 4 is a side view of the luminaire shown in FIG. 1.

The broken lines shown in the drawings illustrate portions of the luminaire that form no part of the claimed design.
